S. D. LITTLEFIELD, OF BURLINGTON, WISCONSIN, ASSIGNOR TO HIMSELF
AND HORATIO D. KNIGHT, OF THE SAME PLACE.

Letters Patent No. 69,350, dated October 1, 1867.

IMPROVEMENT IN AXLES.

The Schedule referred to in these Letters Patent and making part of the same.

TO ALL WHOM IT MAY CONCERN:

Be it known that I, S. D. LITTLEFIELD, of Burlington, in the county of Racine, and in the State of Wisconsin, have invented certain new and useful Improvements in Skeins of Axles; and do hereby declare that the following is a full, clear, and exact description thereof, reference being had to the accompanying drawings, and to the letters of reference marked thereon. In the annexed drawings, making part of this specification—

A represents the axle of a vehicle, and B the skein on the end of said axle. C represents the box, which fits in the hub, and into which the skein passes. d d represent collars, of brass or some other suitable soft metal, which are passed over the skein at each end, resting between the skein and the box, and are for the purpose of forming a suitable soft bearing for the skein. These collars are formed, as seen at their outer ends, with flanges e e', which are bevelled in the manner represented. The flanges e e extend over the collar, at the junction of the skein and axle, and the flanges e' e' extend over the edges of the nut D, which passes on to the end of the skein to keep the wheel on. These collars are provided with the small projections or lugs x x and x' x', which take into recesses formed to receive them in the collar E, and in the skein just back of the screw-thread at the end of said skein. The objects of these lugs or projections are to keep the collars d d stationary upon the skein. These collars d d will be manufactured of suitable sizes, to correspond with the different-sized skeins now in use, and can be applied very readily in a few moments to any skein by any ordinary smith. By the use of these collars, the skein, after it has become worn, can be made to fit the box snugly, and thus do away with that rocking of the wheel upon its axle which is so injurious to it. From the formation of the flanges at e e', sand, or grit, or dirt falling upon them will be readily turned off, so that it will not reach the skein.

I am aware that the use of flanges for covering the collars is not new; but they have not heretofore been bevelled, and consequently do not prevent the egress of the dirt, &c. By bevelling the flanges, as herein described, the axle is kept clean, as the sand and dirt will be prevented from passing into the axle.

Having thus fully described my invention, what I claim as new, and desire to secure by Letters Patent, is—

1. The bevelled flanges e e', for covering the collar E and the nut D, and protecting them from grit and sand, substantially as specified.
2. The projections or lugs x x', for stationing the collars d d temporarily upon the skein, substantially as set forth.

In testimony that I claim the foregoing I have hereunto set my hand this 28th day August, 1867.

S. D. LITTLEFIELD.
